UNITED STATES PATENT OFFICE.

JOHN L. NICHOLSON, OF CHICAGO, ILLINOIS, ASSIGNOR TO LOCOMOTIVE FIREBOX COMPANY, OF CHICAGO, ILLINOIS, A CORPORATION OF DELAWARE.

LOCOMOTIVE BOILER.

Application filed July 14, 1924. Serial No. 725,784.

This invention relates to improvements in locomotive boilers and especially to those boilers having a fire box of the so-called combustion chamber type, and it consists of the 5 matters hereinafter described and more particularly pointed out in the appended claims.

In some locomotive boilers having fireboxes of the combustion chamber type, the height of the throat sheet is, indeed, limited 10 and restricted by various boiler conditions so that it is quite shallow. Great difficulty is presented under such conditions to the installation of water circulating elements in the firebox which connect the said throat sheet 15 with the crown sheet.

It is one of the objects of the present invention to so construct the throat sheet and bottom wall of the combustion chamber, that the inlet end of said circulating element or elements may be operatively connected thereto 20 and to the crown sheet in a manner which permits spacing of said inlet end a sufficient distance above the grate bars, and at the same time provide a front water leg, amply able 25 to meet the demands of the inlet end of said circulating element.

A further object of the invention is to provide an improved construction of water circulating element having a somewhat restricted inlet area, which opens into the lower 30 water leg at the junction of the inner throat sheet and bottom wall of the combustion chamber and having a discharge mouth of a relatively large area which opens through 35 the crown sheet of the boiler.

A further object of the invention is to improve the construction of the water circulating element which is in the form of an inverted substantially triangular and flat body 40 connected at its base to the crown sheet and at its apex by a tubular neck with the junction of the inner throat sheet and bottom wall of the combustion chamber, and to so arrange the front edge or wall of said body that it is 45 inclined upwardly and rearwardly from said neck, thus permitting a certain flexibility of these parts which eliminates buckling or other undue stresses in the expansion or contraction thereof under temperature changes.

These objects of the invention, as well as others, together with the many advantages thereof will more fully appear as I proceed with my specification.

In the drawings:

Fig. 1 is a vertical longitudinal section 55 through the firebox end of a locomotive boiler embodying my invention.

Fig. 2 is a transverse vertical section 60 through the firebox in a plane indicated by the line 2-2 of Fig. 1.

The invention is herein illustrated and will be herein described as embodied in a locomotive boiler having a fire box of the combustion chamber type but, as is apparent, the invention is not to be limited thereto as it 65 may be embodied in locomotive fireboxes of other types, where its peculiar characteristics make it advantageous to do so.

Referring now in detail to the locomotive boiler firebox illustrated herein, the same has 70 a fire chamber which extends from the back sheet 1, to the flue sheet 2, and from one to the other of the side sheets 3-3, with a grate or bottom 4. Said grate, as herein shown, extends from the back sheet to an inner throat 75 sheet 5 which is spaced rearwardly from the flue sheet 2. The top of the firebox is formed by a crown sheet 6 which extends from the back sheet to the flue sheet and between said flue sheet and the inner throat sheet is provided a combustion chamber 7 having its top 80 formed by the crown sheet, its sides 8 formed by end parts or continuations of the side sheets and having its bottom formed by a transversely and upwardly curved bottom 85 wall 9 which merges into the side walls of said combustion chamber and extends from the flue sheet to the inner throat sheet. Said combustion chamber is of a cross sectional area less than that of the firebox, and its bottom wall 9 is inclined upwardly and rearwardly from the flue sheet, said inclination being more pronounced on the longitudinal median line of the boiler, than on either side 90 thereof where it is more gradual because of the merging of the transversely curved bottom wall into the curved side wall parts of said combustion chamber.

At the junction or meeting of the inner throat sheet 5 and the bottom wall 9 of the 100 combustion chamber 7, in the longitudinal median plane of the boiler is provided an annular flange or collar 10 arranged with its axial plane extending upwardly and rearwardly, said annular flange being connected 105 to said inner throat sheet and said bottom wall by an annular corrugation 11 which permits of a limited expansion and contraction.

of said flange or collar under temperature changes in the firebox. Spaced a suitable distance on each side of said annular flange 10 is a similar annular flange or collar 5 10^a—10^a, the number of such collars and the lateral spacing thereof, of course, being dependent upon the size or width of the firebox.

In the rear sheet 1 is provided the usual fuel door opening 12 and to the front or flue 10 sheet 2 are connected the usual flues 13 through which the products of combustion are drawn by the exhaust nozzle (not shown) in the manner well known.

The firebox is enclosed by a top plate 14 and side plates 15—15, the outside throat plate 16 and back plate 17, which provides the wrapper therefor. Said plates, together with the fire sheets or walls of the firebox, define the several water legs of the boiler, 20 namely, the front leg, or throat, 18, the side legs 19—19 and the back water leg 20, all closed at the bottom by the usual mud ring, as shown. The inner sheets of the firebox including the crown sheet are joined to or stayed 25 from the outer sheets of the firebox by means of the staybolts 21.

In the embodiment of the invention herein shown, it will be apparent that the firebox contains a plurality of substantially triangular hollow elements 22, 23 and 24, respectively 30 which conduct water from the front leg 18 of the boiler to the space above the crown sheet 6. Three of such elements are shown herein, but this number of elements is to be 35 considered as illustrative only as I do not limit myself to any particular number of such elements used in the firebox of a boiler. Said elements extend longitudinally of the firebox and are spaced apart laterally so as to occupy 40 parallel planes, one (23) in the longitudinal median plane of the boiler, and flange or collar 10, and the other two (22 and 24) in the planes of the other flanges or collars 10^a—10^a, before mentioned. As all of said 45 elements are alike in construction, a detailed description of one will suffice for all.

Each water circulating element, preferably includes an upwardly and rearwardly inclined tubular neck or bottom 25 and a progressively upwardly enlarging body portion 50 26. The lower part of the bottom portion is a closed tube and constitutes the neck or inlet portion 27 of the element which is in open and unobstructed communication with 55 the water space or leg 18 below the flues 13. As shown herein, the extreme end of said neck portion is seated within one of the flanges 10—10^a and is preferably welded thereto. The portions 25 and 26 merge into 60 long slot-like passageways 28 (see Fig. 2) which register with openings in the crown sheet to have unobstructed communication with the boiler space above the crown sheet. The water may flow and rise freely from the 65 bottom of the boiler, which includes the leg

18, into the water circulating element where it is rapidly heated and rises therein to be discharged above the crown sheet.

The circulating element thus far described is substantially the same in construction and 70 operation as that shown in and termed a "thermic siphon" in Patent #1,337,720, to John L. Nicholson issued on April 20, 1920. As described in said patent, the circulating element is made of a single piece of sheet 75 metal folded upon itself to provide the neck 27 as well as the flared body portion 26 which has an outwardly extending flange 29 at its top. Said flange is preferably welded to the crown sheet about the elongated openings 80 therein which registers with the space 28, before referred to. Said space is defined by parallel side walls 30—30 which are joined together at their forward ends to provide a rounded end wall 31. This rounded end wall 85 is inclined upwardly and rearwardly from the vertical plane of the point of its connection with the neck 27. Said inclination of said end wall is important because it permits of more flexibility of the siphonic element 90 under temperature changes so that it readily accommodates itself to contraction and expansion without buckling, splitting or cracking which, of course, would be indeed serious. Internal strains or stresses in said elements 95 are ably resisted by connecting or staying the side walls of said elements together by means of the stay bolts 32.

Under operating conditions induced by a fire in the firebox, a vigorous flow of water 100 from the lower part of the boiler and upward through the firebox is provided with a copious rapid and widely distributed delivery of water and steam into the space above and on top of the crown sheet of the boiler.

My improved construction has many advantages. The inlet end of the thermic siphonic element is connected to the inner throat sheet without placing it so low as to engage the fire bed on the grate bars which, 110 of course, would be objectionable in that it would interfere with the combustion and might cause burning out of said element at the inlet end thereof. Furthermore the front water leg capacity is increased without material change in the boiler shell or in the bottom wall of the combustion chamber so that the supply of water for the inlet end of the circulating elements is always adequate.

The advantages of the above mentioned 120 construction are, no doubt, apparent to those skilled in the art. In describing the invention, I have referred to certain details of construction, as well as form and arrangement of parts, but it is to be understood that I do not wish to be limited thereto except as may be pointed out in the appended claims.

I claim:

1. A locomotive firebox, in combination with one or more hollow substantially ver- 130

- tical and triangular water circulating elements therein, the top of each element opening through the crown sheet into the space above the same, each element having an intake 5 throat at its lower end through which communication is established with the bottom of the boiler, said element including a front wall which is inclined upwardly and rearwardly from the connection of said wall with 10 the intake throat.
2. A locomotive firebox having a combustion chamber at its forward end and a throat at the rear end of said combustion chamber, in combination with one or more substantially 15 vertical and triangular water circulating elements therein, the top of each element opening through the crown sheet into the space above the same, each element having an intake neck at its lower end which is connected to 20 said throat, said element including a front wall which is inclined upwardly and rearwardly from the vertical plane of the connection of said front wall with said neck.
3. A locomotive firebox comprising a rear 25 fire bed chamber and a front combustion chamber, the bottom wall of which is inclined upwardly and rearwardly to meet the throat sheet at the forward end of said fire bed chamber, means providing a plurality of 30 laterally spaced annular flanges at the meeting parts of said bottom wall and throat sheet, a plurality of hollow substantially vertical and 35 triangular water circulating elements each having a tubular neck portion at its lower end operatively connected to one of said flanges, the other or top ends of said circulating elements being elongated in the longitudinal plane of the firebox and opening through 40 the crown sheet to provide a water circulation between the bottom and top parts of the boiler.
4. A locomotive firebox comprising a rear fire bed chamber and a front combustion chamber, the bottom wall of which is inclined upwardly and rearwardly to meet the throat sheet at the forward end of said fire bed chamber, means providing a plurality of laterally spaced annular flanges at the meeting parts of said bottom wall and throat sheet, a plurality of hollow substantially vertical and 45 triangular water circulating elements each having a tubular neck portion at its lower end operatively connected to one of said flanges, the other or top ends of said circulating elements being elongated in the longitudinal plane of the firebox and opening through 50 the crown sheet to provide a water circulation between the bottom and top parts of the boiler, said elements each including a front wall which is inclined upwardly and rearwardly from the vertical plane of the connection of said wall with said tubular neck portion.
- In testimony whereof, I have hereunto set my hand, this 8th day of July, 1924.
- JOHN L. NICHOLSON.
